UNITED STATES PATENT OFFICE.

HENRY J. CROCKER, OF SAN FRANCISCO, CALIFORNIA.

DESIGN FOR AN INSIDE WRAPPER FOR RAISIN-BOXES.

SPECIFICATION forming part of Design No. 19,874, dated June 3, 1890.

Application filed April 19, 1890. Serial No. 348,747. Term of patent 3½ years.

To all whom it may concern:

Be it known that I, HENRY J. CROCKER, a citizen of the United States, residing at the city and county of San Francisco, State of California, have made certain new and original Designs for Inside Wrappers for Raisin-Boxes; and I do hereby declare the following to be a full and true description thereof.

My invention relates to certain new and original designs in display-sheets for raisin-boxes, of which the following is a full specification, reference being had to the accompanying drawings, forming a part thereof.

Referring to the drawings, Figure 1 is a plan view of the sheet folded, and Fig. 2 a view of the sheet opened.

The letter A represents the entire sheet, which, as shown in Fig. 2, is provided with the end and side flaps $a\ a'$, which are designed to fold or turn over upon the body of the sheet, as fully shown in Fig. 1. The flaps $a\ a'$ leave the inner field B exposed to view, and the side flaps a' are recessed in the arc of a circle, as shown at a^2 .

It is my intention to provide the surface of the inner field and that of the flaps with pictorial representations (not shown in the drawings) indicative of the raisins—such as vine-yard scenes—and, if so desired, the under surface of the flaps may be so ornamented, thereby greatly tending to enhance the appearance of the sheet.

Having thus described my invention, what I claim as new, and desire to secure protection in by Design Letters Patent, is—

The design for inside wrappers for raisin-boxes herein shown and described, consisting of a sheet provided with end and side flaps, the latter being recessed, said end and side flaps being also turned over upon the body of the sheet, so as to leave a central exposed portion, substantially as set forth.

In testimony whereof I affix my signature in the presence of witnesses.

HENRY J. CROCKER.

W. A. SINNERTON,
FRANK H. HILL.
